U.S. PATENT DOCUMENTS

D. 35,539 * 12/1901 Fairweather .

The ornamental design for a junction box cover for a water heater, as shown and described.

DESCRIPTION

FIG. 1 is a front elevation view of a water heater having mounted thereon a junction box cover according to the present invention;

FIG. 2 is a front elevation view of a junction box cover according to the present invention;

FIG. 3 is a side elevation view of the junction box cover of FIG. 2;

FIG. 4 is a top view of the junction box cover of FIG. 2; and, FIG. 5 is a bottom view of the junction box cover of FIG. 2. The broken lines in the Figures are for illustrative purposes only; none of the broken lines form a part of the claimed design. The surface(s) or portion(s) of the article not shown in the drawing or described in the specification form(s) no part of the claimed design.
